PROCESS OF REFINING OILS

Application filed January 4, 1929. Serial No. 330,309.

This invention relates to the treatment of oils and particularly relates to a process of neutralizing and decolorizing oils with finely divided solid adsorbents. Although the process is applicable to the refining of vegetable and animal oils, it is particularly directed to the treatment of petroleum oils such as lubricating oils.

By the use of the term adsorbent as hereinafter applied, we refer to the use of any finely divided or comminuted solid material capable of exerting an adsorbing action upon the oil being treated and including such materials as natural decolorizing or adsorbing clays, acid treated or otherwise activated clays, various forms of carbon, silica and other material.

Most oils such as lubricating oil stocks, are acid treated during refining, and it has been discovered previously that such oils containing small quantities of acid and acid reaction products may be neutralized without the application of alkaline solutions by contact with comminuted solid adsorbents such as the mineral montmorillonite and other decolorizing clays.

When it is desired to neutralize acid oil with a finely divided adsorbent, it is general practice to agitate the acid oil with a quantity of adsorbent sufficient to produce the desired neutralization. In view of the fact that most of these adsorbents exert decolorizing effects upon oil, it is customary to heat mixtures of oil and adsorbent so as to simultaneously neutralize and decolorize the oil, the heat being applied so as to produce temperature conditions which facilitate the decolorizing and neutralizing reactions. This process, while attractive from an operating standpoint, entails the use of large amounts of adsorbents per unit volume of oil treated and, for this reason, the following modification has been suggested as being an economic improvement over the hereinabove described single step treatment.

This second method of treating acid oils so as to produce a neutralized and decolorized oil consists in agitating the acid oil with a decolorizing clay at a moderate temperature so as to gather all suspended sludge and tar

resulting from a previous treatment with acid and then removing the clay together with the sludge and tar by filtration. The cleaned oil, freed of tar and suspended sludge, is then agitated with fresh clay at a moderate temperature, or at a slightly higher temperature, so as to complete the neutralization, and again filtered to remove the clay. The neutralized oil is then contacted with a further quantity of fresh clay, the mixture being brought to a sufficiently high temperature to enable the decolorizing reaction to take place, and again filtered to remove the clay with adsorbed coloring matter.

This invention relates to a process whereby acid oils are neutralized and decolorized with a relatively small quantity of clay, the neutralizing step being carried out by the use of a partially spent clay or other adsorbent. According to this invention, acid oil and partially spent clay or other adsorbent are agitated together at a moderate temperature, say 100-450° F., so as to effect neutralization, such decolorization as takes place at this stage being merely incidental. The proportion of decolorization which takes place in this step depends somewhat upon the character of the oil. After the neutralized oil is separated from this spent clay or other adsorbent, it is then agitated with a relatively small quantity of fresh adsorbent, the mixture being heated to a suitable decolorizing temperature. The adsorbent is then removed from the treated oil in any suitable manner and such removed and partly spent adsorbent may then be utilized for neutralizing a further quantity of acid oil.

The neutralization and major decolorization are therefore accomplished successively, and a different batch of clay is used to complete the decolorizing than that used for neutralizing, it having been found that clay having expended its decolorizing power is still effective as a neutralizing agent. Partially spent clay or other adsorbent which has been spent only in decolorizing oil is used to neutralize the acid oil, any decolorizing power remaining in the partially spent adsorbent acting to partially decolorize the stock during the neutralizing step. After

separation of the completely spent adsorbent from the neutralized stock, fresh clay or other adsorbent is added thereto and the decolorizing operation completed.

5 This cycle may be repeated indefinitely, and may be started by first neutralizing, but not materially decolorizing, a batch of oil with an adsorbent which, at the completion of this neutralizing step, is discarded. The 10 neutralized oil may then be completely decolorized with a fresh batch of adsorbent and such adsorbent, having been partially spent in adsorbing the coloring matter from the oil, may be used for neutralizing a further quantity of oil. The finished neutralized and 15 decolorized oil obtained by this method is generally of better color than that obtained by former methods, while the total amount of adsorbent used per unit volume of finished oil will be found to be from ten to thirty 20 percent less. This great reduction in quantity of adsorbent required to neutralize and decolorize oils is apparently due to the fact that a relatively small quantity of adsorbent 25 will exert a more complete decolorizing effect upon an oil if such oil is first neutralized by means of partly spent adsorbent from such decolorizing reaction.

An object of this invention is to provide a 30 method of neutralizing and decolorizing oils in which the quantity of adsorbent required is materially reduced from that generally required.

Another object is to utilize an adsorbent for 35 neutralizing acid oils, which adsorbent has previously expanded all or part of its decolorizing power on neutralized oil.

Another object is to provide a method of neutralizing and decolorizing acid oils in 40 separate steps.

A still further object is to provide a method of using partially spent adsorbents for neutralizing acid oils.

Another object is to provide a method of 45 neutralizing and decolorizing acid oil in separate steps, the decolorizing step being the source of adsorbent for the neutralizing step.

Other objects and advantages of our process 50 will be apparent from the following description of a process of neutralizing and decolorizing petroleum oils, the application of this process to the treatment of petroleum oils being stated in detail merely for purposes 55 of illustration.

Reference will also be had to the appended drawing, in which the various steps and apparatus required are diagrammatically illustrated. It is to be understood, however, that 60 the hereinafter described detail process may be materially modified without departing from the invention, and the invention is not limited to a process employing all of the steps or the precise apparatus shown in the 65 attached drawing, the invention including

all such modifications as come within the scope of the appended claims.

Generally, in carrying out our process, it is necessary to first obtain a batch of partially spent clay or other adsorbent. For example, 70 it may be obtained by using a batch of clay to decolorize oil which has previously been neutralized by caustic or other agent. The cycle can be most conveniently started by neutralizing an acid oil with a small batch of clay, discarding such clay and then completely decolorizing the neutralized oil with a fresh 75 batch of clay. In the decolorizing operation the clay loses a part of its effectiveness but is still sufficiently active to neutralize acid stock. The partially spent clay is then preferably added direct to a batch of acid oil which is neutralized and also partially decolorized if the clay retains any of its decolorizing properties, the clay being thoroughly mixed with the oil and the mixture heated to a temperature of approximately 80 250° F. or higher and preferably with the use of steam.

The mixture may then be cooled below the 85 temperature of substantial oxidation if the 90 temperature employed in the neutralizing step is such that substantial oxidation of the oil would take place on exposure to the atmosphere, after which the spent clay may be 95 removed from the mixture by filtration or other means of separating solids from liquids and discarded, leaving the neutralized oil in condition for further treatment.

The neutralized oil may be next charged 100 into a treater equipped with means for heating and agitating the contents, and fresh clay added in an amount suitable to accomplish the desired decolorization, as previously determined. The clay is well mixed with the 105 oil and the mixture brought to the proper temperature for decolorization and maintained at such temperature until the decolorizing reaction is completed. While the mixture is being brought up to this temperature, 110 any low boiling constituents which may be present in the oil may be removed by distillation, whereupon the operation may be preferably accompanied by steaming.

The clay used in this step, although its 115 major decolorizing properties are exhausted, still retains its neutralizing power, and after separation from the oil by filtering is retained for use in the neutralization of a fresh batch of acid oil. The hot oil-clay mixture may 120 be sent direct to the filter and the oil cooled after separation or the mixture may be given a complete or partial cooling before filtration. In any event care should be taken to avoid contact with the atmosphere until the 125 temperature of the oil is reduced below that of rapid oxidation. In separating the decolorizing clay from the mixture it is not essential that the partially spent clay be substantially denuded of oil, as any oil entrained 130

in the filter cake is carried over into the fresh batch of acid oil which is to be neutralized by means of the partially spent clay.

While the removal of low boiling constituents from the neutralized oil has been described as taking place after the fresh clay has been added to the neutralized oil, it may be desirable to remove such fractions prior to the addition of fresh clay. This is for the reason that, under some circumstances, the decolorizing operation may be more efficiently carried out on substantially reduced stock. In such cases the neutralized oil may be heated to distill off the low boiling constituents, after which the heated oil may be mixed with the fresh clay and brought to the proper decolorizing temperature. As before, the clay is only partially spent in the decolorizing step, and after being filtered from the oil is used as a neutralizing agent for a fresh batch of acid oil.

Any suitable forms of apparatus may be used in carrying out the process of the invention, which may be performed as a complete cycle or as separate steps as desired, an example of cycle operation being shown in the accompanying drawing.

Referring to the drawing, which represents a flow diagram, the acid oil may enter the system through a line 1 and be mixed with a partially spent adsorbent such as clay which has been partially spent in the decolorization of neutralized oil. Such partially spent adsorbent may be mixed with the acid oil entering the system through line 1 in a suitable mixing device such as the mixing tank 2, the partially spent adsorbent being supplied from a source to be hereinafter described and indicated by line 3. The mixture of acid oil and partially spent adsorbent from the vessel 2 may then be pumped by the pump 4 and through line 5 into another mixing tank 6. Means may be provided for heating the mixture in tank 6, such means being illustrated on the drawing by the heater 7, a portion of the mixture of oil and spent adsorbent being circulated from tank 6 by means of the pump 8 through line 9 into heater 7 and returned to tank 6 through the line 10. Suitable valves such as the valves 11, 12 and 13 may be employed to regulate the flow or circulation of the mixture through the heater 7.

The acid oil is neutralized by the partially spent adsorbent in tanks 2 and 6 and, after such neutralization, the mixture of oil and spent adsorbent may then be passed through line 14 into a cooler 15 where the temperature of the oil may be reduced to below the temperature of rapid oxidation, if such temperatures were reached by passing the oil through the heater 7. Generally, it is not necessary to cool. From the cooler 15 the mixture of oil and spent adsorbent may be pumped by a pump means 16 into a suitable

separating means such as the filter 17, the oil being discharged from the filter by line 18, while the discharge of spent clay is indicated by line 19.

The neutralized oil discharged from the filter 17 by line 18 may then be pumped by pump means 20 and through line 21 into a suitable mixing means such as the tank 22, wherein the neutralized oil is intimately contacted with fresh adsorbent, preferably in finely divided form, supplied through a suitable feeding means such as the hopper 23. If desired, the mixing means 22 may take the form of a tank or treating vessel in which the mixture of oil and clay or other adsorbent may be heated so as to distill off the moisture and low boiling constituents which may be present, for which a vapor outlet 24 may be provided. The neutralized oil, together with fresh adsorbent added thereto, is preferably raised to a sufficiently high temperature to enable the decolorization to take place with greatest efficiency. Such heating may be attained by circulating the mixture of oil and fresh adsorbent from the treating vessel 22 through a line provided with a valve 25 and by means of a pump 26 through a heater 27 which may contain tubes 28.

A line 29 provided with a valve 30 may lead from the heater 27 back to the treating vessel 22, thereby permitting the pump 26 to circulate a certain quantity of the mixture of oil and adsorbent through the heater until the desired temperature is reached. The oil and adsorbent may then be pumped by the means 26 through the lines 28 and 29 into line 31 by closing the valve 30 in line 29 and opening valve 32 in line 31.

The system may also be operated continuously to tank 22 and the material continuously removed through line 31 by regulation of valve 32 or by an additional pump in line 31.

In this manner the heated mixture of oil and adsorbent may be sent to a cooler 33 and therefrom into a suitable separating means such as the filter 34 wherein the decolorized oil may be separated from the partially spent adsorbent. The oil may be discharged through line 35 and, if desired, sent through a secondary cooler 36 before it is sent to a suitable storage, or for further treatment through line 37. The partially spent adsorbent separated from the finished oil in the separating means or filter 34 may then be mixed with acid oil by sending to the mixing tank 2 through a line or other suitable means 3.

By utilizing the process above described, a superior decolorizing effect may be obtained with a much smaller quantity of adsorbent or decolorizing clay than is necessary under methods used heretofore. In some instances the amount of decolorizing clay required has been as low as seventy-five percent of that formerly used. The re-use of the clay in the

manner described has resulted in efficiencies of ten to thirty percent over present methods and materially reduces the cost of neutralizing and decolorizing acid treated oils.

We claim:

- 5 1. The process of refining acid treated oils which comprises heating the acid oil with a comminuted solid adsorbent previously used for decolorizing neutralized oil, separating the adsorbent from the oil, adding fresh adsorbent to the oil, heating the mixture to above 212° F. to decolorize the oil, and finally separating the decolorized oil from the adsorbent.
- 10 15 2. The process of refining lubricating oils containing acid reaction products, comprising agitating partially spent adsorbent with an acid oil in the presence of heat to neutralize the oil, separating the spent adsorbent from the oil, adding fresh adsorbent to the neutralized oil, heating the mixture to above 212° F. to effect a decolorizing reaction on the oil, separating the partially spent adsorbent from the decolorized oil, and then contacting said partially spent adsorbent with a fresh batch of acid oil to neutralize the same.
- 20 25 3. The process of refining acid treated lubricating oils comprising mixing an acid oil with adsorbent partially spent in decolorizing neutralized oil, heating the mixture to about 250° F. to neutralize said acid oil, cooling the mixture below the temperature of rapid oxidation of the oil, separating the neutralized oil from the spent adsorbent, mixing the neutralized oil with fresh adsorbent, heating the mixture to a temperature above about 250° F. to decolorize the oil, cooling the mixture below the temperature of rapid oxidation of the oil, separating the decolorized oil from the partially spent adsorbent, and then contacting the partially spent adsorbent with a fresh batch of acid treated oil to neutralize the same.
